GLASS WASHING MACHINE

Henry C. Husemann, St. Louis, Mo.

Application July 31, 1948, Serial No. 41,775

1 Claim. (Cl. 134—130)

1

This invention relates to glass-washing machines, its principal object being to provide a machine of this kind which, while performing with the maximum of efficiency will at the same time be of such simple construction as to permit its manufacture at the minimum of expense. The most important feature of my machine is that it washes both the inside and the outside of the glasses being cleansed simultaneously, an advantage which I have been unable to find in glass-washing machines heretofore produced. Another advantage of my device is that it requires the minimum of time and attention on the part of the operator, and since it is intended primarily for use in taverns, restaurants, and the like, the saving of the operator's time becomes an important item.

In the drawings—

Fig. 1 is an elevational view of my glass-washing machine illustrating particularly the conveyor and for supporting glasses above the water tank during the cleansing operation.

Fig. 2 is an enlarged cross-sectional view taken on line 2—2, Fig. 1, showing particularly the conveyor and the means for spraying water therethrough.

Fig. 3 is a view taken on line 3—3, Fig. 2, showing a tumbler being subject to simultaneous internal and external cleansing.

Fig. 4 is an enlarged detail view of a section of the conveyor.

Fig. 5 is a cross-sectional view taken on line 5—5, Fig. 4.

The invention comprises a water tank 1 which rests upon a supporting frame having vertical end members A connected by a floor B. At one side of the water tank 1 and near an end thereof a pulley 2 is mounted on an axis 3 which extends interiorly of the tank 1 from side to side thereof and is journaled in the longitudinal walls of said tank. A motor 4 is mounted exteriorly of the tank upon an extension 5 near the pulley 2, said extension projecting outwardly from the wall on which said pulley is mounted, and a belt 6 connects the pulley 2 and the motor 4 for operation of said pulley by said motor. Interiorly of the tank 1 a drum 7 is mounted upon the axis 3 of the pulley 2 for rotation therewith. Also interiorly of the tank 1 and near the end opposite the pulley 2 a drum 8, similar to the drum 7, is rotatably mounted upon an axis 9 extending between and journaled in the longitudinal walls of the tank 1, and a conveyor 10 passes over the drums 7 and 8 so that upon rotation of said drums the conveyor 10 travels longitudinally of the tank

1. The conveyor 10 is of peculiar formation, as will be hereinafter set forth, and from what has been said it is obvious that the conveyor 10 is operated through the agency of the motor 4.

5 A second motor 11 is positioned upon the floor B approximately midway between the end members A, and a pair of pumps 12 and 13, respectively, are also positioned upon the floor B so that there is one of said pumps between the motor 11 and each of the end members A. From an opening 14 in the water tank 1, a pipe 15 leads downwardly to the pump 12. A housing 16 is superimposed upon the water tank 1 and extends upwardly thereover, said housing being of approximately the same length as the frame upon which the tank rests and being of the same width as said tank, and a pipe 17 leads upwardly from the pump 12 to a point somewhat short of the top of the housing 16 and exteriorly of said housing and tank. Through an opening in the side wall of the water tank 1 a horizontal pipe 18 leads from the pipe 17 to the opposite side wall of said tank, where it terminates and is rigidly secured. At the upper extremity of the pipe 17 through an opening in the side wall of the housing 16 a similar horizontal pipe 19 leads from the pipe 17 to the opposite wall of said housing, where it also terminates and is rigidly secured.

20 From an opening 20 in the water tank 1 a pipe 21 leads downwardly to the pump 13, and a pipe 22 leads upwardly from said pump to a point somewhat short of the top of the housing 16, also exteriorly of said housing and tank. Through an opening in the side wall of the water tank 1 a horizontal pipe 23 leads from the pipe 22 to the opposite wall of said tank, where it terminates and is rigidly secured. At the upper extremity of the pipe 22 through an opening in the side wall of the housing 16, a similar horizontal pipe 24 leads

25 from the pipe 22 to the opposite wall of said housing, where it also terminates and is rigidly secured. The upper surfaces of the horizontal pipes 18 and 23 and the lower surfaces of the horizontal pipes 19 and 24 are perforated, as shown at 18' and 19' in the pipes 18 and 19 (Fig. 2), for a purpose to be hereinafter set forth.

30 As mentioned above, the conveyor 10 is of peculiar formation, which will now be described and which is clearly illustrated in Fig. 4. The conveyor comprises a plurality of very small spiral springs 25 closely interlaced as shown in the detail view Fig. 5, and from these two views it will be apparent that this construction offers a multiplicity of very small interstices in the conveyor 10, the close interlacing of the springs 25

at the same time providing the conveyor with a flat surface upon which the glass tumblers being cleansed are supported, as shown in Fig. 3. The purpose of the interstices between the springs 25 will be later set forth.

In operation the procedure is as follows:

Through an inlet pipe 26 water from any convenient source of water supply is permitted to flow continuously into the tank 1, the pipe 26 being provided with a control valve 27 to regulate the flow. At the center of the tank 1 a partition 28 extends upwardly into the tank from the floor thereof, but this partition terminates at a point short of the top of the tank, as shown at 29. Spaced away from the top 29 of the partition 28, a curved supporting member 30 for the lower portion of the conveyor 10 extends transversely across the tank 1, this supporting member being positioned at such height as to lift this portion of the conveyor slightly, the purpose of the supporting member 30 being to provide a space between the conveyor and the partition top 29. From the above it will be seen that the partition 28 divides the tank into chambers C and D which communicate through the space between the conveyor and the partition top 29, so that water flowing into the tank chamber C through the inlet 26, as mentioned above, will flow over the partition 28 and into the chamber D.

Through the opening 14 some of the water in the chamber C of the tank 1 flows down through the pipe 15 to the pump 12, whence, through the agency of the motor 11, it is pumped up through the pipe 17 and into the transverse pipes 18 and 19. In the same manner, some of the water in chamber D of said tank flows down from the opening 20 through the pipe 21 to the pump 13, whence, also through the agency of the motor 11, it is pumped up through the pipe 22 and into the transverse pipes 23 and 24.

When the motor 4 is set in motion, through the agency of the belt 6 it rotates the pulley 2 and therefore the axis 3 and the drum 7 mounted thereon, and since the conveyor 10 passes over both the drums 7 and 8 it is obvious that rotation of the drum 7 will, by virtue of the conveyor 10, also rotate the drum 8; that is to say, while the motor 4 is in operation the conveyor 10 will travel continuously through rotation of the drums 7 and 8.

Near the end of the structure where water flows into the tank through the inlet 26 and positioned above the tank, I provide a container 31 for a non-toxic sterilizing agent, said container being provided with a pipe 32 through which the sterilizing agent is dropped at predetermined intervals into the chamber C of the water tank. Each of the end walls of the housing is cut out to permit the glasses being cleansed to enter and leave said housing, and to prevent splashing of water through said cut-outs I suspend curtains 33 and 34, respectively, inside the housing near the cut-outs. These curtains are of light, flexible, waterproof material, for instance, plastic. At the end of the tank opposite the end where the water inlet 26 is located I provide a water outlet 35.

The structure is now ready for the reception of glass tumblers E to be cleansed, as follows:

A tumbler E is placed by the operator upon the portion of the conveyor which extends above the chamber D, so that as the conveyor travels it will carry said tumbler along and the tumbler will enter the housing 16 through one of the cut-outs, the flexibility of the curtain 33 permitting it to be pushed aside by the entering tumbler. As the

tumbler E continues to travel it reaches a position between the perforated pipes 23 and 24, and still continuing its progress it reaches a position between the perforated pipes 18 and 19; and the further progress of said tumbler on the moving conveyor 10 pushes aside the flexible curtain 34 and carries the tumbler through the cut-out at that end of the housing 16 and beyond said housing, and upon its emergence from the housing it may be lifted from the conveyor by the operator.

As said above, during its progress the tumbler E passes, respectively, between the pipes 23 and 24 and between the pipes 18 and 19. The action of these two sets of pipes is identical, and for the sake of brevity I will describe here and have illustrated in Fig. 3 the action as taking place when the tumbler is in position between the pipes 18 and 19. It will be remembered that the pump 12 pumps water through the said transverse pipes and that such pipes are perforated as at 18' and 19', respectively. It will also be recalled that the conveyor 10 is of peculiar construction which has been described above, and that it includes a multiplicity of small interstices between a multiplicity of small spiral springs 25. As the water in the tank chamber A is pumped into the pipe 18 it escapes therefrom through the perforations 18' and passes through such interstices in the conveyor, and due to the peculiar formation imparted to the conveyor by the interlaced spiral springs, as the water is sprayed therethrough it attains a whirling motion, shown at 36 in Fig. 3, and from this figure it will be seen that such whirling spray has the effect of cleansing the entire inside of the tumbler E. At the same time the water escaping from the transverse pipe 19 through the perforations 19' sprays the outside of the tumbler E. Thus it is obvious that both the inside and the outside of the tumbler are being simultaneously cleansed without manipulation thereof by the operator.

From the above description it will be understood that the conveyor travels in a direction to carry the tumblers from a position over the chamber D to a position over the chamber C of the water tank 1. However, the flow of water in the tank is in the opposition direction, since the inlet 26 is in the chamber C and the outlet 35 in the chamber D. As the water enters the chamber C it is constantly being sterilized from the container 31, and this water flows from the chamber C into the chamber D over the partition 28 through the space between the top 29 of that partition and the supporting member 30 over which the conveyor 10 passes.

As the soiled tumblers are carried on the conveyor over the chamber D they reach a position between the perforated transverse pipes 23 and 24, where they are subjected to the same spraying action of the water as previously described in connection with the pipes 18 and 19. It is obvious that the first washing of the glasses therefore takes place over the chamber D, and the water which has been soiled from such contact with the soiled tumblers falls back into said chamber through the interstices of the conveyor 10. The glasses continue to travel on the conveyor and thus come over the chamber C and reach the position previously described between the transverse perforated pipes 18 and 19 for the spraying which also has been previously described. However, at this time the tumblers are already comparatively clean from their first cleansing between the pipes 23 and 24, so that the water which falls back into the chamber C

through the conveyor interstices from the perforated pipes 18 and 19 is cleaner than that in the chamber D, and also the water in the chamber C is being constantly replenished with fresh water through the inlet 26. Therefore, it will be seen that the water sprayed on the glasses from the chamber C to give them their final rinsing is fresh as well as being sterilized and completes the cleansing operation which was commenced between the pipes 23 and 24. The soiled water, of course, is constantly escaping through the outlet 35.

As the tumblers continue to travel on the conveyor after their final rinsing, they leave the housing 16 by pushing up the flexible curtain 34 and passing through the cut-out in the housing at that end, whereupon the operator lifts the clean glasses from the conveyor and they are ready for further use.

I claim:

A glass-washing machine comprising pairs of water-ejecting elements for simultaneously cleansing the interior and exterior of the glasses being washed, a movable member on which said

glasses are carried to positions for said simultaneous interior and exterior cleansing, means for continuously moving said movable member, and means for continuously supplying water to said pairs of elements, said movable member being located between one element of each pair of water-ejecting elements and the glasses being washed, and being formed of a multiplicity of small spiral springs to permit passage of water from one element of each of said pairs of elements therethrough and simultaneously convert such water into a whirling mist.
